ATTORNEYS.

A loose-leaf binder, or the like, is an article of manufacture which is designed to hold a sheaf of loose sheets firmly in place upon a support, the support being so constructed that the sheaf may be used as a note pad in any of a plurality of positions. The holder may also be used to bind loose record sheets.

UNITED STATES PATENT OFFICE

2,164,496

LOOSE LEAF BINDER

Raymond S. Brown, Columbus, Ind.

Application November 25, 1936, Serial No. 112,684

17 Claims. (Cl. 129—35)

The present application relates to a loose-leaf binder, and more particularly to an article of manufacture so constructed and designed as to hold a sheaf of loose sheets firmly in place upon a support, the support being so constructed that the sheaf may be used as a note pad in any of a plurality of positions. The holder may also be used to bind loose record sheets.

The primary object of the invention is to provide a device of the character indicated which shall be extremely inexpensive to manufacture and which shall, nevertheless, possess the advantages and desirable characteristics required, in such a device, for perfect satisfaction to the user. Further objects of the invention will appear as the description proceeds.

To the accomplishment of the above and related objects, my invention may be embodied in the forms illustrated in the accompanying drawings, attention being called to the fact, however, that the drawing is illustrative only, and that change may be made in the specific constructions illustrated and described, so long as the scope of the appended claims is not violated.

Fig. 1 is a broken perspective view of one embodiment of my invention;

Fig. 2 is a similar view of another form of the invention, a sheaf of sheets being shown in place on the support;

Fig. 3 is a fragmental bottom plan of a detail of construction of the structure of Fig. 2;

Fig. 4 is a fragmental perspective view of a third embodiment of my invention;

Fig. 5 is a similar view of a fourth embodiment thereof;

Fig. 6 is a similar view of a fifth embodiment thereof;

Fig. 7 is a similar view of a sixth embodiment thereof;

Fig. 8 is a similar view of a still further form of my invention; and

Fig. 9 is a fragmental central longitudinal section through the embodiment of Fig. 1.

Referring more particularly to Fig. 1, it will be seen that I have illustrated a loose-leaf holder comprising a support which consists of a base 10 having ears 11 and 12 projecting upwardly from its opposite lateral edges. At one end, there is provided an abutment wall 13 which is flanked by ears 14, 14. Adjacent its mid-point, the abutment wall 13 is formed with a notch 15 the lateral edges of which are serrated to form teeth 16.

A bail or clamping member is indicated generally by the reference numeral 17. This member

is of U-shaped configuration, having a bail 18 and 19 which are pivotally connected to ears 11 and 12, respectively. Said legs 18 and 19 merge respectively into substantially aligned sections 21 and 20 which, in effect, constitute a transverse element joining the free ends of the legs 18 and 19, thereby producing a U-shaped bail member.

Substantially at the mid-point of the transverse element 20, 21, the wire is twisted, as at 22, to form an upwardly and outwardly extending stem and a loop 23 which, as is clearly illustrated, constitutes a finger lever and is bent to form the portions 24 and 25 which incline downwardly and outwardly.

In use, a sheaf of sheets is placed in position on the support 10 and preferably against the abutment wall 13. The ears 14 and the bail legs 18 and 19 cooperate to hold the sheaf against lateral displacement.

If, now, the loop 23 is pressed downwardly into the notch 15, it will be seen that the transverse element 20, 21 of the bail will be pressed into contact with the uppermost sheet of the sheaf, and the portions 24 and 25 of the loop will be engaged by certain of the teeth 16 on each side of the notch 15. The transverse element thus acts to clamp the sheaf in place on the base, and serves as a tearing edge against which sheets may be torn away.

The loop is so dimensioned that, in order to enter the portions 24 and 25 of the loop between the lateral edges of the notch 15, it is necessary to flex the transverse member 20, 21, moving the stem 22 away from the ears 11 and 12. This movement of the stem and loop takes place automatically as the loop is depressed, the inclined portions 24 and 25 camming against the tooth surfaces. The downward slant of the portions 24 and 25 of the loop 23 makes it necessary, in order to disengage the loop from the teeth 16, to depress the extremity of the loop still further, as a preliminary to shifting the loop toward the left, as viewed in Fig. 1, to disengage the sides of the loop from the teeth 16.

It will be seen that, when the loop 23 is pressed downwardly to clamp the transverse element 20, 21 against the sheaf of sheets on the support 10, the transverse element 20, 21 is flexed in a direction away from the ears 11 and 12 and is simultaneously placed under torsional stress; and that, at the same time, the legs 18 and 19 (which might also be termed levers) are placed under

bending stress in a direction substantially perpendicular to the plane of the support 10.

The structure of Fig. 2 is, in most respects, identical with the structure of Fig. 1. The support 30 is provided with ears 31 and 32, with an abutment 33, and with ears 34-34. The abutment is notched, as at 35, and the lateral edges of the notch 35 are serrated to form teeth 36. A bail 37, formed of spring wire, is bent to provide legs 38 and 39 and a transverse element 40, 41; and the wire is bent to form a double stem 42 leading to a loop or finger lever 43, the portions 44 and 45 of the loop being downwardly and outwardly inclined. In this figure, I have shown a sheaf 46 of loose sheets clamped in place by the bail 37.

In this embodiment of the invention, I have illustrated a plate, indicated generally at 47, to which may be applied an advertising message, the user's name, or any other desired indicia or legend. As is more clearly illustrated in Fig. 3, the plate 47 is provided with a tongue 48 which is loosely folded over the transverse element 40, 41; and with separate tongues 49 which, at the opposite ends of the plate, are wrapped around the transverse element 40, 41, forming hinges at points on this element which have little radial movement relative to the aligned axes when the element is flexed. As a result of this construction, the transverse element 40, 41 in its position between the two plate surfaces is free to flex away from the aligned axes of the legs 38 and 39 without affecting the position of the plate.

The elements of the stem 42 of the loop 43 are confined by the folded-over edge 147, of the plate, and they project through a slot 148 formed in the curl of said edge. Movement of the loop 43 toward the base 30 when compressing the pad causes the plate to rotate downwardly on its hinges 49. The elements of the stem 42 are not necessarily joined in this construction as the plate furnishes the tearing edge for detaching leaves and a break in the continuity of the element 40, 41 is not detrimental.

In Fig. 4, I have illustrated a further form of my invention comprising a base or support 50 the lateral edges of which are turned under as at 51 and 52. At one end, the base 50 is provided with an upstanding abutment 53 which is flanked by ears 54, 54. A space or slot 55 is provided between one of the ears 54 and the adjacent end of the abutment 53, and said end of the abutment is formed with downturned teeth 56, as is clearly shown.

In this form of the invention, the bail 57 is formed of spring wire and is bent to form a leg 58 merging with a transverse bar 60, the wire passing, at the juncture of the leg 58 and the bar 60 through a slot 59 formed in the curl of the lateral edge 51 of the base. The bar 60 passes beneath the base 50 and emerges through a slot 61 in the curl of the lateral edge 52 of the base; the wire then continuing to form a leg 62 parallel to the leg 58, and a transverse element 63 substantially parallel with the bar 60. At a proper point, the wire is turned upon itself to form a loop 64 in which is engaged an eye 65 formed at the free end of the leg 58. In effect, the legs 58 and 62 and the transverse element 63 comprise a U-shaped bail.

From the loop 64, the wire continues as an arm or finger lever 66 preferably terminating in a ring 67 which is positioned beyond the abutment 53.

Preferably, I provide a plate 68, made of any

desired material, held in place by the inturned edges 51 and 52 of the base, and grooved to receive the bar 60. The plate 68 acts as a spacer and helps to stiffen the base 50.

It will be clear that, when a sheaf of sheets has been placed upon the base 50 in engagement with the abutment 53, the finger lever 66 may be pressed downwardly and engaged beneath one of the teeth 56. When it is so pressed downwardly, torsional stress is impressed upon the transverse element 63, and bending stress is applied to the leg 62. Leg 58 acts as a guide to position loop 64 and to preserve alignment of sheets in the pad. In order to release the finger lever 66 from the teeth 56 it is, of course, necessary to depress the end 67 of the finger lever 66.

Preferably, the abutment 53 is provided with a finger notch 69, for removing stubs.

By omitting leg 58 I have substantially the construction shown in Fig. 6 except that leg 62 is confined to movement in a vertical plane.

In Fig. 5, I have illustrated a form of the invention which is similar to those illustrated in Figs. 1 and 2; but which differs therefrom in that, in order to disengage the loop from its co-operating teeth, it is necessary to move the loop toward the aligned pivotal axes of the bail legs.

In this form of the invention, there is provided a base 70 having lateral ears 71 and 72 and an upstanding abutment 73 at one end of the base, said abutment being flanked by ears 74. The abutment is provided with a notch 75 the lateral edges of which are formed with teeth 76.

The bail 77 comprises a single piece of spring wire bent to provide legs 78 and 79 which merge into substantially aligned sections 80 and 81 cooperating to form a transverse member. The wire is twisted to form a stem 82 projecting substantially from the mid-point of the transverse element 80, 81 and to form a loop or finger lever 83. The sections 84 and 85 of the loop 83 are inclined downwardly and inwardly and are adapted to be engaged with the teeth 76 of the notch 75. In order to release the loop 83 from the teeth 76, it is necessary to depress the loop and to force the same toward the right, thereby flexing the transverse element 80, 81 toward the ears 71 and 72. When the loop 83 is forced into engagement with the teeth 76, torsional and bending stresses are applied to the transverse element 80, 81, and bending stresses are applied to the legs 78 and 79.

In Fig. 6, I have illustrated a form of the invention similar to the form illustrated in Fig. 4, except that the bail is a substantially Z-shaped element, pivoted at one point only. In this form of the invention, the base 90 is formed with a single ear 91 on one lateral edge, and is provided with an upstanding abutment 92 flanked by ears 93. Between one of the ears 93 and the adjacent end of the abutment 92, there is formed a slot 94, and the adjacent end of the abutment 92 is formed to provide downturned teeth 95.

In this form of the invention, the bail, indicated generally at 96, constitutes a single piece of spring wire bent to form a single leg 97, a transverse element 98, and a finger lever 99. Intermediate its ends, and at the point at which the finger lever 99 is adapted to engage one of the teeth 95, said finger lever is bent to provide a V 100; and the finger lever terminates in a ring 101. Preferably, the abutment 92 is formed with a finger notch 102.

When a sheaf of sheets is placed upon the base 75

90; the finger lever 99 may be pressed downwardly to force the transverse element 98 against the face of such sheaf, whereafter further depression of the ring 101 will apply torsional stress to the transverse element 98 and bending stress to the leg 97. The V 100 is provided to prevent any possibility of shifting of the bail 96 about a vertical axis after engagement of the finger lever with one of the teeth 95. Obviously, in order to release the finger lever 99 from its engaged tooth, it is necessary preliminarily to depress the ring 101.

In the five forms of the invention thus far discussed, it will be clear that the construction is such as to make it possible to use therewith sheets which are unpunched and uncut. In the forms of the invention illustrated in Figs. 7 and 8, the construction is such that it is desirable to slot the ends of the sheets for cooperation with the illustrated abutments.

Referring particularly to Fig. 7, it will be seen that I have illustrated a base 110 provided with ears 111 and 112 upstanding from its lateral edges. At one end, the base 110 is provided with an abutment 113 which projects upwardly through a slot 114 in said base, being held in place by flanges 115 and 116 suitably secured to the bottom of the base 110. On its edge remote from the ears 111 and 112, the abutment 113 is provided with a series of teeth 117.

The bail 118 of this embodiment of my invention is formed from a single piece of spring wire bent to form parallel legs 119 and 120 pivotally secured to the ears 111 and 112. Said legs merge into sections 121 and 122 cooperating to form a transverse element. Substantially at the midpoint of the element 121, 122, the wire is twisted to form a stem 123 terminating in a loop or finger lever 124. A sheet metal band 125 is secured to opposite edges of the loop 124 and thereby becomes part of the loop and provides means for engagement with the teeth 117.

It will be clear that, when a sheaf of sheets is placed upon the base 110 (said sheets preferably being notched to fit around the abutment 113), the loop 124 may be moved toward the base to engage the transverse element 121, 122, with the surface of the sheaf; and said loop 124 may then be further depressed into engagement with a selected one of the teeth 117. Such further depression of the loop 124 places the transverse element 121, 122, under torsional and bending stresses, and places the legs 119 and 120 under bending stresses. In order to release the loop 124 from its engagement with the teeth 117, it is necessary to pull said loop away from the ears 111 and 112, thereby further flexing the transverse element 121, 122.

In Fig. 8, there is illustrated a base 130 provided with lateral ears 131 and 132 and with an abutment 133 which preferably projects into slots in the sheets and which comprises a strip of metal folded upon itself and then bent outwardly to form oppositely projecting flanges 134 and 135, the outer edges of which are serrated to form teeth 136 and 137, respectively.

In this form of the invention, the bail 138 is formed of a single piece of spring wire bent to provide legs 139 and 140 pivotally connected to the ears 131 and 132 and merging into sections 141 and 142 cooperating to form a transverse element. Substantially from the mid-point of the transverse element 141, 142 there projects a stem formed by twisting the wire as at 143, and said stem merges into a loop or finger lever 144

which is bent, as at 145 and 146. It will be seen that the teeth 136 and 137 engage points inside the loop 144; and that the plane of the loop slopes downwardly and toward the ears 131, 132, in that portion of the loop which is engaged by the teeth 136 and 137. Since the said teeth engage the loop on a chord located between the ears 131 and 132 and that major chord of the loop which is parallel with the transverse element 141, 142, it is necessary, in order to disengage the loop from said teeth, to move said loop toward the base 130 and toward the ears 131 and 132.

When the loop 144 is engaged with the teeth 136 and 137, the transverse element 141, 142 is under torsional and bending stresses and the legs 139 and 140 are under bending stresses.

It will be seen that, in the embodiments of Figs. 1, 2, and 5, the teeth of the abutment elements engage the outer sides of the loops on non-diametrical chords; that in the embodiment of Fig. 20, the teeth of the abutment element engage the inner sides of the loop upon a non-diametrical chord; that in the embodiment of Fig. 7, the teeth of the abutment element engage a band 125 carried by the loop; and that in the embodiments of Figs. 4 and 6, the teeth of the abutment element engage an unlooped finger lever. It will also be seen that, in the embodiments of Figs. 1, 2, and 7, disengagement of the loop or finger lever from the cooperating teeth involves movement of the finger lever toward the base and away from the pivotal axes of the bail legs; that in the embodiments of Figs. 5 and 8, disengagement of the finger lever from the cooperating teeth involves movement of the finger lever toward the base and toward the pivotal axes of the bail legs; and that in the embodiments of Figs. 4 and 6, disengagement of the finger lever involves movement of the finger lever toward the base and in a direction substantially parallel with the ends of the base.

It will further be clear that whereas, in the embodiment of Figs. 1, 2, and 8, the abutment teeth engage points on the loop on non-diametrical chords thereof disposed between the transverse element and that major chord of the loop which is parallel with the transverse element; in the embodiment of Fig. 5, the abutment teeth engage points on the loop on a non-diametrical chord separated from the transverse element by 50 that major chord of the loop which is parallel with said transverse element.

In all of the embodiments of the invention herein disclosed, a space for advertising, or the like, not readily available for memorandum writing, is provided between the transverse bail element and the adjacent end of the sheet. In the embodiments of Figs. 4, 6, 7, and 8, the stubs remaining after sheets have been torn from the pad against the transverse element, may be readily removed without releasing the clamping bail.

I claim as my invention:

1. A loose-leaf binder comprising a base for supporting a sheaf of sheets, and a spring wire bail comprising at least one leg pivoted on a lateral edge of said base intermediate the ends thereof and a transverse bar projecting from the free end of said leg toward the opposite edge of said base, a finger lever projecting from said bar substantially parallel with said leg, and means 65 cooperable with said finger lever for holding the latter in a position in which said bar is pressed against the face of said sheaf under torsional stress while said leg and said finger lever are subjected to bending stress.

2. A loose-leaf binder comprising a base for supporting a sheaf of sheets, and a spring wire bail comprising a substantially U-shaped member having its legs hinged to opposite lateral edges of said base upon aligned axes, a wire loop projecting substantially from the mid-point of the transverse element of said U-shaped member, and notched means on said base cooperable with said loop, at times, to hold the same in a position 10 in which said transverse element is pressed against the face of said sheaf under torsional stress and the legs of said U-shaped member are subjected to a bending stress.
3. A loose-leaf binder comprising a base for supporting a sheaf of sheets and formed to provide an upstanding abutment at one end thereof, and a spring wire bail comprising a U-shaped member having its legs pivoted on opposite lateral edges of said base upon aligned axes, a spring 15 wire element projecting from the transverse element of said U-shaped member toward said abutment, and tooth means formed on said abutment and cooperable with said spring wire element, at times, to prevent movement of said transverse 20 element away from said base.
4. A loose-leaf binder comprising a base for supporting a sheaf of sheets and formed to provide an upstanding abutment at one end thereof, and a spring wire bail comprising a U-shaped 25 member having its legs pivoted on opposite lateral edges of said base upon aligned axes, a spring wire loop projecting substantially from the mid-point of the transverse element of said U-shaped member toward said abutment, and tooth means 30 formed on said abutment and cooperable with said loop, at times, to prevent movement of said transverse element away from said base.
5. A loose-leaf binder comprising a base for supporting a sheaf of sheets and formed to provide an upstanding abutment at one end thereof, and a spring wire bail comprising a U-shaped 35 member having its legs pivoted on opposite lateral edges of said base upon aligned axes, a spring wire loop projecting substantially from the mid-point of the transverse element of said U-shaped member toward said abutment, and tooth means 40 formed on said abutment and engageable with the opposite sides of said loop upon a non-diametrical chord thereof, at times, to prevent movement of said transverse element away from said base.
6. A loose-leaf binder comprising a base for supporting a sheaf of sheets and formed to provide an upstanding abutment at one end thereof, and a bail comprising a pair of legs pivoted on 45 opposite lateral edges of said base upon aligned axes and a transverse resilient member connecting the free ends of said legs, a loop element projecting from said resilient member toward said abutment, and tooth means formed on said abutment and engageable with said loop, at times, upon flexing of said resilient member, to hold 50 said resilient member against movement away from said base.
7. A loose-leaf binder comprising a base for supporting a sheaf of sheets and formed to provide an upstanding abutment at one end thereof, and a bail comprising a pair of legs pivoted on opposite lateral edges of said base upon aligned 55 axes and a transverse resilient member connecting the free ends of said legs, a loop element projecting from said resilient member toward said abutment, and tooth means formed on said abutment and engageable with the opposite sides of said loop upon a non-diametrical chord there- 60
- of, at times, upon flexing of said resilient member, to hold said resilient member against movement away from said base.
8. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable with the opposite sides of said loop upon a non-diametrical chord thereof, located between said resilient member and the major chord of said loop parallel with said resilient member, at times, upon flexing of said resilient member, to hold said resilient member against movement away from said base.
9. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable with the opposite sides of said loop upon a non-diametrical chord thereof, located beyond the major chord of said loop parallel with said resilient member, at times, upon flexing of said resilient member, to hold said resilient member against movement away from said base.
10. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable within said loop, at times, upon flexing of said resilient member, to hold said resilient member against movement away from said base, said abutment including an upstanding member lying in the median longitudinal plane perpendicular to said base and adapted to be received in a slot formed in an end of said sheaf.
11. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable with points on the outside surface of said loop, at times, upon flexing of said resilient member, to hold said resilient member against movement away from said base.
12. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable with said loop, at times,

upon flexing of said resilient member away from said aligned axes, to hold said resilient member against movement away from said base.

13. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, and tooth means formed on said abutment and engageable with said loop, at times, upon flexing of said resilient member toward said aligned axes, to hold said resilient member against movement away from said base.

14. A loose-leaf binder comprising a base for supporting a sheaf of sheets, and a clamping member comprising at least one lever hinged to said base, a bar extending from the free end of said lever across said base and adapted to engage said sheaf, means cooperating with said bar for impressing a torsional stress on said bar and a bending stress on said lever to hold said sheaf in place on said base, and a sheaf-engaging plate hinged to said bar and swingable about the axis of said bar in response to movement of said cooperating means.

15. A loose-leaf binder comprising a base for supporting a sheaf of sheets and formed to provide an upstanding abutment at one end thereof, and a bail comprising a pair of legs pivoted on opposite lateral edges of said base upon aligned axes and a transverse resilient member connecting the free ends of said legs, a loop element projecting from said resilient member toward said abutment, tooth means formed on said abutment and engageable with said loop, at times, upon

flexing of said resilient member to hold said resilient member under bending stress and under torsional stress, and a sheaf-engaging plate hinged to said resilient member at points near its junctions with said legs, and movable in response to movement of said loop in applying such torsional stress but unresponsive to bending of said transverse member. 5

16. A loose-leaf binder comprising a base for supporting a sheaf of sheets and formed to provide an upstanding abutment at one end thereof, and a bail comprising an integral length of spring wire bent to form a U-shaped member from the transverse element of which projects a loop, the legs of said U-shaped element being pivoted upon aligned axes on said base, and means on said abutment cooperable, at times, with said loop to hold said loop against movement away from said base. 10

17. A loose-leaf binder comprising a base for supporting a sheaf of sheets and formed to provide an upstanding abutment at one end thereof, and a clamping member comprising at least one lever pivoted on a lateral edge of said base and a transverse element carried by the free end of said lever and adapted to engage said sheaf on a line substantially parallel with said base end, a finger lever projecting from said transverse element toward said base end, and means on said abutment engageable, at times, with said finger lever to hold said transverse element against movement away from said base, said last-named means and said finger lever being formed with cooperating surfaces enforcing movement of said finger lever toward said base as a preliminary to disengagement of said finger piece from said last-named means. 20 25 30 35

RAYMOND S. BROWN.

CERTIFICATE OF CORRECTION.

Patent No. 2,164,496.

July 1, 1939.

RAYMOND S. BROWN.

It is hereby certified that error appears in the printed specification of the above numbered patent requiring correction as follows: Page 4, second column, line 55, claim 11, after the word "one" insert end; and that the said Letters Patent should be read with this correction therein that the same may conform to the record of the case in the Patent Office.

Signed and sealed this 15th day of August, A. D. 1939.

Leslie Frazer

(Seal)

Acting Commissioner of Patents.
